UNITED STATES PATENT OFFICE.

CHARLES B. RICHARDS, OF CLEVELAND, OHIO, ASSIGNOR, BY MESNE ASSIGNMENTS, TO THE CLEVELAND ROCK DRILL COMPANY, OF CLEVELAND, OHIO, A CORPORATION OF OHIO.

WATER ATTACHMENT FOR DRILLING-MACHINES.

1,059,563.

Specification of Letters Patent.

Patented Apr. 22, 1913.

Application filed June 2, 1909. Serial No. 499,731.

To all whom it may concern:

Be it known that I, CHARLES B. RICHARDS, a citizen of the United States, residing at Cleveland, in the county of Cuyahoga and State of Ohio, have invented certain new and useful Improvements in Water Attachments for Drilling-Machines, set forth in the following specification.

The invention relates to attachments for supplying water or other fluid forwardly through the drill during the drilling operations, and has for its principal objects; the provision of an improved and advantageous arrangement of the water ring with respect to the drill parts; the provision of an arrangement whereby the drill may be changed or renewed without interference with the water supply attachment; and the provision of an improved means for mounting the water ring. Certain embodiments are illustrated in the accompanying drawings, whereforein:

Figure 1 is a longitudinal section through the drilling machine embodying the invention,

Figure 2 is an enlarged partial section through the front end of the piston and water ring, and

Figure 3 is a section on the line III--III of Figure 2.

In drilling machines as heretofore constructed, fluid has been usually conducted to the passage through the drill in one of the following ways. A water ring provided with a passage communicating with the passage in the drill was mounted on the drill itself; or fluid was supplied to the passage in the drill by means of a passage through the piston carrying the drill, such latter passage communicating with a passage leading through the portion of the machine in which the piston was mounted for reciprocation.

In the first instance, more or less difficulty was experienced in maintaining the water ring upon the drill, and a change in the drill required a change of the water ring; and in the second instance, an expensive and somewhat complicated arrangement of passages and packing members was required, and leakage to the cylinder of the machine was liable to occur. My invention is designed to overcome the foregoing objections by a simple and inexpensive arrangement,

which briefly stated, consists in mounting the water ring upon the piston in the novel and effective manner hereinafter more particularly set forth.

Referring now to the drawings and particularly to Fig. 1, the principal parts may be enumerated as follows. 1 is the cylinder of the machine which may be of any approved form; 2 and 3 are passages through which fluid is alternately supplied and exhausted from the opposite ends of the cylinder; the valve mechanism for controlling such passages being immaterial insofar as the present invention is concerned, and not shown; 4 is the main or body portion of the piston, which piston is provided at its front portion with the stem 5, and enlarged part 6 (Fig. 2); 7 is what may be termed the water ring although other fluids than water may be supplied thereto if desired, such ring being swiveled upon the enlarged part 6 of the piston; 8 is a chuck member preferably integral with the enlarged part 6; and 9 is the drill, which may be of any approved form, and which is held in the chuck in the usual manner by means of a key 10, and a U bolt 11.

The manner in which the water ring is mounted upon the enlarged part 6, and in which fluid is supplied from such water ring to the drill is best shown in Figs. 2 and 3. As here shown the drill is provided with the longitudinally extending passage 12 which passage registers at its rear end with a passage 13 in the enlarged part 6. The water ring has its interior diameter increased at 14 so as to provide a continuous passage 15 about the periphery of the enlarged part 6, and the passage 13 communicates with this annular passage 14. The ring is supplied with a fluid inlet passage 16, the supply hose being attached to the portion 16. Leakage is prevented by means of the pair of U shaped rubber members 17. The collar 19 upon the forward end of the enlarged part 6 prevents forward movement of the ring, and a split collar 20 screw threaded upon the part 6 and held securely in position by means of a transverse bolt 21 (Fig. 1), prevents rearward movement of the ring. The main body portion 4 of the piston is made of less diameter than that portion of the part 6 upon which the ring 7 swivels, so that

the ring may be made in one piece and can be positioned by slipping it over the portion 4 before inserting the piston in the cylinder.

It will be seen from the foregoing that the 5 construction is a simple and inexpensive one, not liable to leakage, and that the drill may be removed and replaced without interference with the water supply device applied to the part 6. It will also be seen that the 10 parts may be readily assembled, and that when in assembled position such parts are securely maintained.

Having thus described my invention and 15 illustrated its use, what I claim as new and desire to secure by Letters Patent is the following:—

1. In combination in a fluid operated drilling machine, a piston, a stem at the front thereof, an enlarged part at the front 20 end of the stem of a diameter greater than that of the piston, a drill secured in the front end of the enlarged part and provided with a passage, stop means on the enlarged part, a one piece water ring swiveled on the 25 enlarged part and held against forward movement by the stop means, and a split detachable collar secured to the enlarged part at the rear of the water ring, the enlarged part being provided with a passage 30 communicating with the passage in the drill, and the water ring being provided with a water inlet passage communicating with the passage in the enlarged part.

2. In combination in a fluid operated drilling machine, an operating member comprising a piston and a stem, an enlarged portion at the front end of said stem of greater diameter than the piston and provided with a shoulder and with a water passage, a chuck to the front of the enlarged portion, a one piece water ring swiveled on the enlarged portion and bearing against the shoulder, a split holding collar threaded on the enlarged portion to the rear of the water ring, and means for clamping the collar 45 tightly upon the enlarged portion.

3. In combination in a fluid operated drilling machine, an operating member comprising a piston and a stem, an enlarged portion at the front end of said stem of greater diameter than the piston and provided with a shoulder and with a water passage, a chuck to the front of the enlarged portion, a one piece water ring swiveled on the enlarged portion and bearing against the shoulder, a split holding collar threaded on the enlarged portion to the rear of the water ring, and threaded means for clamping the ends of the collar together.

In testimony whereof I have hereunto 60 signed my name in the presence of the two subscribed witnesses.

CHARLES B. RICHARDS.
